BASKET MAKING MACHINE AND METHOD

Albert H. Schmidtke, St. Joseph, Mich., assignor
to St. Joseph Iron Works, St. Joseph, Mich., a
corporation of Michigan

Application May 20, 1932, Serial No. 612,395

21 Claims. (Cl. 1—13.6)

My invention relates to the making of rectangular or oblong baskets and has reference more particularly to the shifting of the form in a direction transverse to its axis of rotation for locating the ends and sides of the baskets in proper positioning for stapling, and the adaptability of the form for free rotation at required times.

In the manufacture of certain kinds of baskets wherein an oblong or other non-circular form is employed to support the work as fasteners are applied thereto it is desirable to shift the form transversely of the axis of rotation to clear the fastener setting mechanism and locate the various portions of the work in proper position for applying fasteners thereto and moreover in some baskets, particularly where a hoop strip forms the inner and outer binding for the upper edge of the basket, it is desirable to release the form so as to permit an initial turn thereof for winding a portion of the hoop strip on the form before the basket is placed in position thereon.

The principal objects of my invention are to provide improved apparatus for the manufacture of baskets; to improve the facilities for adjusting the form transversely to its axis of rotation so as to properly position the various portions of the basket for operation thereupon by the fastener applying mechanism; to permit freedom of rotation of the transversely shiftable form at suitable times for winding a hoop strip thereon; to lock the form in a central position against lateral shifting when free to rotate; and in general, to provide a simple and dependable machine which may be readily used without difficulty by an ordinary operator to make baskets rapidly and satisfactorily.

On the drawings:

40 Fig. 1 is a side view of the machine;

Fig. 2 is a perspective view of the upper portion of the machine showing the front and the side opposite to that of Fig. 1;

Fig. 3 is an enlarged view, partly in vertical section, of the form and its mounting and shows the form released for free rotation;

Fig. 4 is a view similar to that of Fig. 3 but showing the form in the stapling position;

Fig. 5 is an enlarged detail view taken on the line 5—5 of Fig. 3;

Fig. 6 is an enlarged sectional view on the line 6—6 of Fig. 4;

Fig. 7 is a fragmentary detail perspective view of the wiper for holding the hoop strip against the basket side wall;

Fig. 8 is a fragmentary detail of the loose connection through which the hoop strip guide is controlled; and

Fig. 9 is a perspective view of the basket which the illustrated machine is designed to make.

Referring to the drawings the reference numeral 10 indicates the base of the machine which has a hollow standard 11 extending upwardly therefrom. A shaft 12 is mounted to slide vertically in the standard 11 and has secured to its upper end the bracket 13 which carries the movable staple forming and driving parts of a pair of staplers 14 and 15 the stationary parts of said staplers 14 and 15 being mounted on the bracket 16 which is secured to or formed as a part of the upper end of the standard 11. A drive shaft 17 is journaled in bearings 18 and 19 at the base of the machine and extends within the lower end of the standard 11 where it is connected in the usual manner with the upright shaft 12 so that the latter is reciprocated to cause the stapling mechanisms 14 and 15 to perform a single stapling operation in each revolution of said drive shaft 17.

A drive pulley 20, through which power is applied for operating the machine is mounted to rotate freely around the drive shaft 17 and has a clutch connection with the said shaft. This clutch connection which is of the one revolution type and arranged for disengagement at a suitable point in the rotation of the shaft 17 so that the machine stops with the staple forming and driving parts in the upraised position, is controlled by the trip member 21 which slides in the bracket 22 to and from the clutch releasing position, being normally held inwardly in said position by the spring 23. A shaft 24 which is journaled at its rear end in the bracket 22 and at its forward end in the bracket 25, has an upstanding arm 26 operatively connected with the sliding trip member 21, and near the front of the machine this shaft 24 is provided with a laterally extending pedal 27, pressure on the tread portion of which rocks the shaft 24 and the upstanding arm 26 in a direction to withdraw the trip member 21 from the clutch disengaging position and permit the drive pulley 20 to connect with and rotate the shaft 17. The shaft 17 continues to rotate with the pulley 20 as long as the pedal 27 is maintained in the depressed position, and upon release of said pedal the spring 23 returns the trip member 21 to the clutch releasing position wherein it disengages the clutch at the point in the revolution of the shaft 17 wherein the stapling devices are in the upraised position. To insure

prompt stopping of the shaft 17 when the clutch is released a brake drum 23 on said shaft is engaged by a brake band 29 which is so arranged that it has merely sufficient retarding action to 5 accomplish the required purpose.

A form upon which the basket parts are assembled and fastened together is mounted on the standard 11 at a convenient elevation and adapted to be rotated, the shaft through which power is 10 applied for rotating the form being indicated at 30 and journaled in the bearing portion 31 of the bracket 32 which is secured by bolts 33 to the standard 11 at the proper elevation. This shaft 30 has a housing 34 fixed on the rear end containing a suitable frictional connection with the sprocket 35 so that the latter rotates the shaft 30 through this frictional connection except at such 15 times as the housing 34 is held against turning movement at which time the frictional connection 20 permits the necessary slippage between the sprocket 35 and the shaft 30.

This sprocket 35 is connected by the chain 36 with the sprocket 37 on the shaft 17 so that the sprocket 35 is constantly driven while the machine is in operation. The housing 34 is provided at suitable intervals around its periphery with stop lugs 38 with which the stop member 39 engages, said stop members 39 being on the upper end of the rod 40 which slides in the bearing 41 and is normally held upwardly by the spring 42 to position the stop member 39 in the path of movement of the stop lugs 38. On the lower end of said rod 40 is a fitting 43 which straddles the shaft 17 and is provided with a roller 44 positioned 35 to be engaged by a cam 45 on the shaft 17 so that the rod 40 is depressed at a certain time in the revolution of the shaft 17 to release the stop member 39 from the stop lug 38 with which it is engaged and permit rotation of the shaft 30 through 40 the sprocket 35 and the friction connection in the housing 34, the cam 45 being so arranged that the stop member 39, after each releasing operation, is returned by the spring 42 to the upraised position in ample time to engage the next succeeding stop lug 38 so that at each release the shaft 30 turns only that portion of a revolution measured by the circumferential distance between the stop lugs 38.

Details of the construction of the friction driving connection in the housing 34 and of the clutch that connects the drive pulley 20 with the shaft 17 are not given as these as well as the other parts of the mechanisms that effect the operation of the staplers and the step by step rotation of the shaft 30 are well known and in use in basket making machines.

The shaft 30 does not extend through to the front of the machine or support the basket form but terminates at a cut out or recess 46 in the 60 top of the bracket 32 where it is provided with a coupling head 47 which has a pair of diametrically disposed openings 48. A hollow shaft or spindle 49 is mounted in the bearing portion 50 of the bracket 32 in axial alignment with the shaft 30 and fixed on the rear end of this shaft or spindle 49 is a coupling head 51 which has a pair of diametrically disposed rearwardly extending pins 52 which are adapted to engage in the 65 openings 48 of the coupling head 47 for connecting the shaft or spindle 49 with the shaft 30 for rotation in unison therewith, the rear ends of the pins 52 being suitably rounded as shown in Figs. 3 and 4 to facilitate entry thereof into the openings 48.

75. The basket form 53 which is of an oblong, sub-

stantially rectangular and slightly tapered form suitable for making what are known as "Carrier" or "Till" baskets is mounted on the outer or forward end of the shaft or spindle 49 and supports the work for operation upon by the staplers 14 and 15 which co-operate respectively with the clinch cavities 54 and 55 at the ends and sides of the form for fastening a band or hoop strip to the upper edge portion of the side wall of the basket, and in order that in the stapling operation the ends of the form will be presented at substantially the same elevation as the sides, the form 53 is arranged to slide in the direction of its length across the end of the shaft or spindle 49 and facilities are provided which serve, as the 10 spindle or shaft 49 rotates, to slide the form downwardly as each end comes up into the stapling position.

For slidably mounting the form 53 on the end of the shaft or spindle 49 the latter is formed at 20 its forward end with a substantially square or rectangular head 56 which slidably engages in a slot 57 in the thick wall 59 of the form, which said slot extends in the direction of the length of the form and is of sufficient length to permit the necessary endwise movement of said form, the form being retained on the head 56 by the flange or shoulder 60 at the rear side of the wall 59 and the plate 61 which is clamped against the forward end of the head 56 by the bushing 62 which 30 is threaded into an enlarged threaded recess in the head 56.

A roller 63 is provided on form 53 near each end of and extending rearwardly from the wall 59 and the forward end of the bracket 32 is formed with a face plate portion 64 to which is attached a cam 65 of suitable contour to fit between the rollers 63 and co-operate therewith in the rotation of the shaft or spindle 49 in a manner to centralize the form 53 on the end of the shaft or spindle 49 40 at the central position of the form in its translation across the axis of rotation, which said position is shown in Fig. 6 and hereinafter referred to as the midway position, as each side of the form 53 is presented upwardly to the staplers 14, 45 15 and to slide the form downwardly as each end of the form comes up to the stapling position and thereby not only insure clearance between the staplers and the ends of the form as the latter is rotated but also insure the location of the ends 50 at the same fixed distance from the staplers as the sides of the form in the stapling operations.

The cam 65 is arranged eccentrically with respect to the shaft or spindle 49 as shown in Figs. 2 and 6 so as to effect the required downward shifting of the form and the peripheral form of the cam is such that all opposed points of engagement of the rollers 63 therewith are uniformly spaced apart, said cam however being preferably formed with a slot 66 extending upwardly from the bottom to facilitate the mounting of the cam with the shaft or spindle 49 extending therethrough. This affords a satisfactory construction as the sides of the cam leading to the open lower end of the slot 66 insure proper guiding of the form to the point wherein the weight of the form holds the upper roller 63 engaged with the top of the cam 65.

In making baskets of the type shown in Fig. 9 which the illustrated machine is designed to produce, the bottom and side walls are formed of two crossed pieces 67 and 68 of veneer which have their end portions bent upwardly to form the side walls which have their upper edge portions stapled between inner and outer portions 75.

of a retaining hoop strip or band 69 which is wound once around the form and then after the pieces 67 and 68 are shaped in basket form on the form 53 with the upper edge portions 5 of the side walls lapped over the previously wound portion of the band 69, is wound again around the form over the upper edge portions of the basket side walls and stapled thereto.

It is desirable to apply the first or inner winding 10 of the band 69 by hand and to manually turn the form at the time and for this reason the shaft or spindle 49 if of such length and the cut out place 46 in the bracket 32 of sufficient width to permit the form 53 to be pulled forwardly by the operator a sufficient distance to 15 be entirely withdrawn from under the staplers 14, 15 and at the same time the coupling member 51 is separated from the coupling member 47 to disengage the pins 52 from the openings 20 48 so that the shaft or spindle 49 is free to turn. This forward movement of the form 53 also withdraws the rollers 63 from the cam 65 and when this takes place it is desirable to lock the form 53 centrally on the head 56 against end-wise sliding movement.

In the present machine the final stapling operation which completes the basket leaves the form 53 with a side of the form facing upwardly as shown in Figs. 1, 3, 4, and 6 in which position the form is centrally located on the head 56 by the interengaged cam 65 and rollers 63 and a locking device is provided which works automatically, as the form is pulled out, to lock the form in this position on the head 56 and to release same when the form is returned to the position under the staplers. To accomplish this automatic locking and release of the form, a rod 70 extends through the hollow shaft or spindle 49 and the bushing 62 and at the outer 40 end within the hollow form 53 this rod 70 is bent back as shown in Figs. 3 and 4 to provide a laterally offset rearwardly extending end 71 which is engaged in a notch or recess 72 in the edge of the plate 61 and is adapted to engage 45 a central notch 73 in the flange 74 which extends along one side of the opening 57 in the wall 59 of the form. A similar flange 75, which need not be centrally notched, extends along the other side of the opening 57, both of these flanges 50 76 and 75 as well as the rear face of the wall 59 being faced off to insure proper thickness and satisfactory sliding engagement between the plate 61 and the flange or shoulder 60 of the head 56.

The other end of the shaft or rod 74 has a collar or sleeve 76 fixed thereon and sliding in an enlarged opening 77 in the rear end of the shaft or spindle 49, which said opening 77 contains a spring 78 which exerts a tension on the collar 76 to face the rod 70 rearwardly so that the back turned forward end 71 will engage the notch 73 to lock the form 53 centrally on the head 56. This however can only occur when the form 53 is pulled forwardly from under the staplers 14, 15 as the form must be capable of sliding on the head 56 when said form is located under the staplers and the rollers 63 are engaged with the cam 65, and the shaft or rod 70 is accordingly extended rearwardly a sufficient distance so that when the form 53 is pushed rearwardly to the stapling position and the coupling members 47 and 51 are coupled together, the rear end of the shaft or rod 70 engages the coupling member 47 and the rod is thus pushed forwardly against the tension of the spring 78

a sufficient distance to free the end 71 of the said rod or shaft from the notch 73 so that the form 53 is free to slide on the head 56.

For locating and holding the initial winding of the band 69 on the form 53 the latter has a flange 79 therearound which is cut away as at 80 adjacent the clinch depressions 54 and 55 to accommodate the staple holders or guides which are pressed against the work in the stapling operation, and this flange is provided at 10 each end and at each side of the form with a forwardly extending pin 81 under which the initial winding of the hoop or band 69 is engaged and by which it is held in place as the basket is formed and applied thereto.

For shaping and holding the basket pieces 67, 68 on the form a form hood 82 is mounted to move to and from the front of the form, said form hood in the present structure comprising a plate 83 with a wing member 84 secured thereto along 20 each lateral edge and a wing member 85 secured thereto along each end edge which co-operate respectively with the side and end walls of the form 53 to shape and hold the basket pieces 67 and 68 therebetween in the form of the basket. 25 This hood is supported on the upper end of an arm 86 which is pivoted at its lower end to the machine base 19 to permit the necessary movement of the upper end to and from the front of the form 53, a weight 87 being attached to the 30 arm 86 at or near the lower end to impel the upper end of the arm 86 toward the form 53 and a pedal 88 being provided, pressure upon which serves to overcome the weight 87 and swing the upper end of the arm 86 away from the form.

The upper end of the arm 86 has a socket portion 89 in which the stem 90 is secured so that it is in axial alignment with the form supporting shaft or spindle 49 when said arm 86 is in the position to hold the form hood 82 on the form 53 and this stem has a circular disk like head 91 on its inner end for rotatably and slidably supporting the form hood 82, said head 91 being spaced from the socket portion 89 of the arm 86 by a shoulder 92 on the stem 90. Any convenient 45 arrangement may be employed for attaching the form hood 82 on the head 91 of the stem 90, the present arrangement comprising a pair of guides 93 along opposite edges of a spacing plate 94 on the outer face of the hood plate 83 forming 50 a channel for the head 91 which is held therein by overhanging plates 95, the latter of which together with the guides 93 are secured to the hood plate 83 by the screws 96. With this construction the form hood is capable of rotation 55 about the axis of the stem 90 and its circular head 91 and may also slide laterally on the head 91, the extent of this sliding movement being determined by the heads 97 of the cap screws that are employed at the ends of the spacing plate 94 for securing the latter to the hood plate 83, it being understood of course that the extent of sliding movement of the form hood 82 on the head 91 is sufficient to correspond to the sliding movement of the form 53 on the supporting head 60 56 of the form supporting shaft or spindle 49.

In making a basket with this machine the machine stops after each basket has been completed, with the form in the position shown in Figs. 1, 4 and 6 wherein a side of the form 53 is presented upwardly to the staplers 14 and 15 which have just completed the last stapling operation on that side of the form. The operator then presses his foot on the pedal 88 and swings the form hood 82 away from the form 53 so that the completed 70 75

basket may be removed and during or after the removal of this completed basket the form 53 is pulled forwardly from under the staplers 14, 15 thereby disengaging the coupling members 47 and 51 and at the same time releasing the rod 70 so that the end 71 thereof locks the form 53 in the central position on the head 56. The operator then slips the end portion 98 of the band 69 under the pin 81 at the top side of the form and turns the latter by hand three quarters of a revolution in a clockwise direction, wrapping said band around the form and engaging it under the succession pins 81 and against the flange 78 at the end of which proceeding the form is in the vertical position with the band 69 projecting laterally to the left from the upper left hand corner of the form. The veneer blanks 67 and 68 which have previously been scored along the fold lines are then folded over the form and the latter indexed another quarter turn to the horizontal position shown in Fig. 6 wherein the strip or band 69 overlies the initial end portion 98 with an edge portion of the veneer blank 67 therebetween and the form is then pushed back under the staplers, at which time the pins 52 of the coupling member 51 are in position to engage the openings 48 of the coupling member 47 and the rollers 63 likewise in position to engage the cam 65 which preferably has the edges beveled as at 99 to facilitate such engagement, and it is understood that the engagement of the coupling members 51, 47, engages the rear end of the rod 70 with the coupling member 47, thereby releasing the locking engagement of the other end 71 of said rod with the notch 73 of the form so that the latter is now free to slide on the head 56 to follow the contour of the cam 65.

In the further operation of making the basket the projecting portion of the strip or band 69 is wound around the form as the latter is turned to the successive stapling positions and to effect this winding of said projecting portion of the strip or band 69 a holder or guide is provided with which the projecting portion of the strip or band 69 is engaged in the operation of pushing the form back to the stapling position. This holder or guide is mounted on the laterally offset portion 100 of the shaft 101 which is engaged through a vertical slot 102 in a lateral extension 103 of the bracket 32, the shaft 101 being threaded and provided with a clamped nut 104 at each side of the extension 103 for rigidly securing the shaft in any desired position of adjustment in the slot 102. A bracket 105 has a hub portion whereby it is secured by set screws 106 on the offset portion 100 of the shaft 101 and this bracket has an elevated plate like extension 107 with a forwardly extending substantially horizontal flange 108 on which the projecting portion of the strip or band 69 is placed when the form 53 and basket parts thereon are pushed back to the stapling position.

A lever 109 is pivoted at 110 to the portion 107 of the bracket 105 and extends laterally from said pivot over the flange 108 toward the form and cooperates with said flange 108 to form a holder and guide through which the strip or band 69 is drawn onto the form by the rotation of the latter, the strip being held between said lever 109 and flange 108 against rearward displacement by the plate like extension 107 of the bracket 105 and against forward displacement by the lug 210 which is on the lever 109 and arranged so that in the depressed clamping position of said lever it overlaps the forward edge of the flange 108 while

in the raised position of said lever it is elevated sufficiently so that the projecting portion of the strip or band 69 may be readily inserted between the lever 109 and flange 108. A spring plate 111 which is secured to the under side of the lever 109 extends beyond the end of the latter under the stapler 14 and is arranged so that when the lever 109 is depressed it holds the strip 69 down against the top edge portion of the basket on the form. This spring plate holds the strip 69 substantially at the location where the stapler 14 operates on the basket and to provide clearance for the stapling operation this spring plate is offset laterally at its outer end as indicated at 112 and provided with an angular notch 113 through 15 which the stapler 14 operates.

A spring 114 is arranged to exert a constant tension to swing the lever 109 downwardly to the strip clamping position but this lever is controlled by the clutch operating shaft 24 so that 20 it is held in the elevated position against the tension of said spring 114 except at such time as the pedal 27 is depressed to cause the stapling mechanisms to operate and the form to rotate. To this end the bracket 105 has a depending arm 25 115 which has the lever 116 pivoted thereto at 117 and this lever has its longer arm connected by the link 118 to a crank arm 119 on the clutch controlling shaft 24 so that when the pedal 27 is depressed to engage the clutch through which the 30 machine is operated, the link 118 is pulled downwardly and the lever 116 rocked on its pivot 117. The shorter end of the lever 116, which by reason of this connection is swung upwardly when the clutch pedal 27 is depressed, is connected by the 35 link 120 with the outer end of the lever 109, and in order to leave the lever 109 free to be held downwardly in the clamping position by the spring 114 and capable of some oscillation that may be necessary as the corners of the form 53 40 pass under the end of the plate spring extension 111, the link 120 has a slot 122 at its upper end, as shown in Fig. 8, through which the connecting pin or bolt 123 engages so that when the lever 109 is in the clamping position it is permitted a certain freedom of movement and its clamping pressure is occasioned by the tension of the spring 114.

After the form 53 with the basket parts thereon has been pushed rearwardly and the projecting portion of the strip 69 placed in the hoop guide 50 107-108, the pedal 88 is released so that the weight 87 swings the upper end of the arm 86 rearwardly to engage the form hood 32 and hold the veneer blanks 67 and 68 in shape on the form, in which position said form hood also holds the form in the fully retracted stapling position. The operator then presses on the pedal 27 so as to set the stapling and form turning mechanisms in operation and preferably holds the pedal depressed until the entire stapling operations on 60 the basket have been completed.

Immediately upon pressure being applied to the pedal 27 the clamping lever 109 is released to engage and hold the strip or band 69. At the same time the clutch mechanism is operated to 65 establish a driving connection between the pulley 20 and the shaft 17 which results first in the release of the stop member 39 from the stop lug 38 of the friction connection and the turning of the form 53 a quarter turn from the horizontal position (shown in Fig. 6) to the vertical position and at the same time draws the strip 69 across the upper end of the form, after which the first stapling operation occurs in which the 75

two staplers 14 and 15 operate simultaneously to drive the staples 14^a and 15^a respectively through the several layers of the strip 69 and the edge of the veneer blank 68 therebetween 5 at the upper end of the form. The form 53 is then rotated another quarter turn and the strip 69 drawn across the side wall of the basket and the staples 14^b and 15^b driven, then upon another quarter turn of the form the staplers 14^c, 10 and 15^c are driven, after which the form is turned to the final position in which the staples 14^d and 15^d are driven, the staple 14^d being located adjacent the final end of the strip 69 which was held in place by the end of the spring plate 111 as it 15 was secured in place by the staple 14^d.

As the final stapling operation occurs the operator releases the pedal 27 so that the clutch trip member 28 returns to position to release the clutch and stop the machine with the staplers 20 in the raised position and this leaves the form in the horizontal position shown in Fig. 6 with the cam 45 on the drive shaft 17 ready to release the friction drive 34 and turn the form a quarter turn before the first stapling operation occurs 25 when the pedal 27 is again depressed.

The pedal 88 is then depressed to withdraw the form hood 82 from the form 53, the completed basket removed and the machine is then ready for the assembling and stapling of another 30 basket.

While I have shown and described my invention in a preferred form, I am aware that various changes and modifications may be made without departing from the principles of my invention, the scope of which is to be determined by the appended claims.

I claim as my invention:

1. In an apparatus of the class described the combination of a rotatable form which is reciprocable in a direction transverse to its axis of rotation, means with which the form rotatively co-operates to reciprocate the form simultaneously to or from its midway position during each quarter rotation of the form, and fastener applying mechanism adapted to co-operate with the form to apply fasteners to the work at intervals between quarter rotations of said form.

2. In an apparatus of the class described the combination of a rotatable form which is reciprocable in a direction transverse to its axis of rotation, stationary means co-operating with the form to reciprocate said form to or from its midway position during each quarter rotation of the form, and fastener applying mechanism adapted 55 to co-operate with the form to apply fasteners to the work on the form at intervals between quarter rotations of said form.

3. In an apparatus of the class described the combination of a rotatable form which is reciprocable in a direction transverse to its axis of rotation, means co-operating with the form and serving through and simultaneously with the rotation of said form to effect a gradual reciprocal movement of the form to or from its midway 65 position during each quarter rotation of the form, and fastener applying mechanism adapted to co-operate with the form to apply fasteners to the work on the form.

4. In an apparatus of the class described the 70 combination of an elongated rotatable form slideable longitudinally in a direction transverse to its axis of rotation, means whereby the form is gradually moved longitudinally to a central position relative to the axis of rotation during rotation of the form from vertical to horizontal posi-

tions, and fastener applying mechanism adapted to co-operate with the form to apply fasteners to the work on the form.

5. In an apparatus of the class described the combination of an elongated rotatable form adapted to move longitudinally in a direction transverse to its axis of rotation, a stationary cam, roller means on the form engaged with the cam so that the latter reciprocates the form transversely to its axis of rotation simultaneously as the form is rotated, and fastener applying mechanism adapted to co-operate with the form to apply fasteners to the work on the form.

6. In an apparatus of the class described the combination of a rotatable form, means for moving the form in a direction transverse to its axis of rotation, said form being loosely mounted in a manner whereby it is movable axially to and from engagement with said means, and fastener applying mechanism co-operable with said form to apply fasteners to the work on the form.

7. In an apparatus of the class described the combination of an elongated rotatable form which is movable longitudinally in a direction transverse to its axis of rotation, means for simultaneously rotating the form and moving the form transverse to its axis of rotation, said form being loosely mounted in a manner whereby it is movable axially to and from engagement with said means, and fastener applying mechanism co-operable with the form to apply fasteners to the work thereon.

8. In an apparatus of the class described the combination of a rotatable form, stationary means cooperating with the form to move said form in a direction transverse to the axis of rotation of the form as the form is rotated, and fastener applying mechanism co-operable with the form to apply fasteners to the work thereon, 35 said form being loosely mounted in a manner whereby it is releasable from the said stationary means by axial movement thereof from the fastener receiving position.

9. In an apparatus of the class described the combination of an elongated rotatable form 45 adapted to move longitudinally in a direction transverse to its axis of rotation, a cam, roller means on the form engaged with the cam so that the latter reciprocates the form transversely to its axis of rotation as the form is rotated, said form being loosely mounted in a manner whereby it is movable to release said roller means from said cam by a relative axial movement thereof, and fastener applying means co-operable with 50 the form to apply fasteners to the work on the form.

10. In an apparatus of the class described the combination of fastener applying means, a rotatably mounted form with which the said means 60 co-operates to apply fasteners to the work on the form, said form being axially movable to and from the position in which it co-operates with the fastener applying means, and said form being shiftable transversely to its axis of rotation when 65 in position to co-operate with the fastener applying means and being locked against transverse shifting when moved axially from said position.

11. In an apparatus of the class described the 70 combination of fastener applying means, a rotatably mounted transversely elongated form with which said means co-operates to apply fasteners to the work on the form, said form being axially movable to and from the fastener re- 75

- ceiving position and longitudinally shiftable in a direction transverse to its axis of rotation, a cam for controlling the longitudinal shifting of the form, said form being disconnected from said cam and locked against longitudinal shifting when moved axially from the fastener receiving position.
12. In an apparatus of the class described the combination of fastener applying means, a rotatably mounted transversely elongated form with which said means co-operates to apply fasteners to the work on the form, said form being axially movable to and from the fastener receiving position and longitudinally shiftable in a direction transverse to its axis of rotation, and form rotating mechanism, said form being disconnected from said mechanism and locked against longitudinal shifting and free to rotate when moved axially away from the fastener receiving position.
13. In an apparatus of the class described the combination of fastener applying means, a rotatably mounted transversely elongated form with which said means co-operates to apply fasteners to the work on the form, said form being longitudinally shiftable in a direction transverse to its axis of rotation, a cam for controlling the longitudinal shifting of the form, means for locking the form against said longitudinal shifting, and a form rotating mechanism, said form being movably axially away from the fastener receiving position and by such movement disconnected from the form rotating mechanism and from said cam and locked against longitudinal shifting.
14. In an apparatus of the class described the combination of a pair of aligned rotatable shafts one of which is movable axially to and from operative connection with the other shaft and the latter of which said shafts is operatively connected with a form rotating mechanism, a transversely elongated form mounted on the axially movable shaft so as to slide longitudinally in a direction transverse to the axis of said shaft, a stationary cam, means on the form engaging the cam whereby the latter controls the longitudinal sliding movement of the form, fastener applying means positioned to co-operate with the form, and a lock for holding the form against longitudinal sliding movement, said form being disconnected from said cam and locked against longitudinal sliding movement when the axially movable shaft is moved axially from operative connection with the shaft of the form rotating mechanism.
15. In an apparatus of the class described the combination of a pair of aligned rotatable shafts one of which is movable axially to and from operative connection with the other shaft and the latter of which is operatively connected with a form rotating mechanism, a stapling mechanism, a form mounted on said axially movable shaft and slidable in a direction transverse to the axis of said shaft, and a lock for holding the form against transverse sliding movement, said lock including a member which extends longitudinally within the axially movable shaft and is actuated by the separation of said shafts.
16. The method of making baskets and the like which comprises axially withdrawing from a fastener receiving position a rotatable form which is shiftable in a direction transverse to its axis of rotation and simultaneously with such withdrawal disconnecting the form from a rotating mechanism and from a transverse shifter and locking the form against transverse shifting, then manually rotating the form and winding a portion of a hoop strip around the form, then applying and shaping on the form and over the wound portion of the hoop strip, basket materials that constitute the bottom and side walls of the basket and returning the form to the fastener receiving position, and simultaneously with the return of the form to said position connecting the form with said rotating mechanism and with the transverse shifter and releasing the transverse shifter lock, and then rotating the form in a step by step manner by said rotating mechanism and simultaneously winding and fastening the remaining unwound portion of the hoop strip around the basket materials and over the previously wound portion of said hoop strip.
17. In a machine for making oblong baskets and the like, the combination of a rotatable spindle, a longitudinally reciprocable oblong form mounted on the spindle to rotate therewith, fastener applying mechanism co-operating with the form to apply fasteners to the work on the form, and means co-operating with the form to reciprocate the latter to or from its midway position during each quarter turn of the spindle, said spindle and form being simultaneously and correspondingly rotatable a quarter turn at each interval between fastener applying operations of the fastener applying mechanism.
18. In a machine for making oblong baskets and the like, the combination of a rotatable oblong form, a spindle on which the form is mounted to reciprocate longitudinally in a direction transverse to the axis of the spindle, fastener applying mechanism co-operable with the form to apply fasteners to the work on the form, and means whereby the form is reciprocated to or from its midway position during each quarter turn of the spindle, said spindle and form being simultaneously and correspondingly rotatable a quarter turn at each interval between fastener applying operations of the fastener applying mechanism.
19. In a machine for making oblong baskets and the like, the combination of a rotatable and longitudinally reciprocable oblong form, a spindle on which the form is mounted, fastener applying mechanism co-operable with the form to apply fasteners to the work on the form, and means whereby the rotary movement of the form is utilized to simultaneously effect a positive reciprocation of the form to or from its midway position during each quarter turn of the spindle, said spindle and form being simultaneously and correspondingly rotatable a quarter turn at each interval between fastener applying operations of the fastener applying mechanism.
20. In a machine for making oblong baskets and the like, the combination of a rotatable form, mechanism operable to automatically rotate the form in four successive quarter-turn steps, fastener applying mechanism automatically operable during the interval between each of said quarter turn steps to co-operate with a side of the form and apply fasteners to the work on the form, and means whereby the form is simultaneously shifted lengthwise to or from a position concentric with its axis of rotation during each of said quarter-turn steps of the rotation of the form.
21. In a machine for making oblong baskets and the like, the combination of a rotatable form, mechanism operable to automatically rotate the

form in four successive quarter-turn steps, fastener applying mechanism automatically operable during the interval between each of said quarter-turn steps to co-operate with a side of the form and apply fasteners to the work on the form, and means whereby the form is moved dur-

ing certain quarter-turn steps of its rotation to a position concentric with its axis of rotation and is moved during other quarter-turn steps of its rotation from said position.
